FLEXIBLE TUBE SPRINKLER

Ralph J. Oace, St. Paul, Minn.

Application November 29, 1951, Serial No. 258,848

4 Claims. (Cl. 299—65)

This invention relates to lawn sprinklers or spraying nozzles, and specifically to nozzles comprising a free-ended flexible tube.

One object of the invention is to provide a sprinkler which produces a wedge-shaped spray by a controlled uniplanar to-and-fro motion, under the impelling force of the escaping liquid, of a free-ended flexible tube. Such a spray covers a wedge-shaped area of the lawn from a position at the tip of the wedge, rather than a circular area from a central position as in prior art flexible tube sprinklers. The wedge-shaped spray makes it possible to direct the stream accurately and to move the sprinkler while in full operation. The initially flat or uniplanar spray does not dig into the turf near the foot of the sprinkler, as do the cone-shaped sprays of previously known flexible tube sprinklers when such sprinklers are directed horizontally.

Another object of the invention is to provide for simple but effective control and regulation of the whipping free-ended tube, so as to ensure operation in a flat rather than cone-shaped spray and through a restricted arc.

A further object is to provide a novel type and form of free-ended flexible tube for use in a sprinkler or spraying nozzle as above described.

These and other objects and advantages of my invention are obtained by providing a free-ended flexible tube having a differential flexing action, so that its ability to flex or bend is much greater in one axial plane than in others, and by then mounting such tube with the plane of its maximum flexibility in the plane of the desired flat wedge-shaped spray.

With the flexible tube thus formed and mounted, passage of water under pressure through the tube and out of the free end is found to set up a whipping action in the tube, the free end of which is impelled rapidly from side to side. The tube bends to and fro in the direction of maximum flexibility, being prevented from going too far in either direction within such plane by the tension set up in the corresponding stretched side. The considerable difference in flexibility of the tube between the plane of maximum flexibility and the plane of minimum flexibility at right angles thereto permits the tube to oscillate readily in the former plane without any significant extent of motion in the latter. The stream of water coming from the free end of the tube thus forms a flat wedge in the plane of greatest flexibility of the tube. In the sprinkler as it is used in sprinkling a lawn, for example, the motion of the tube is substantially wholly from side to side, and correspondingly substantially completely lacking in the vertical plane. As the water then falls freely from its initial direction of travel as a wedge-shaped spray, it uniformly covers a wedge-shaped area of the lawn or soil.

One specific example of my novel lawn sprinkler or spraying nozzle is represented in the accompanying drawing, in which Figure 1 is a side elevation of the sprinkler, partly in section, and Figures 2—4 are cross-sectional views of the flexible tube.

The sprinkler 10 of Figure 1, shown partly in section, includes a hollow body portion 11, internally threaded for attachment as a cap to a garden-hose screw connection, having attached at one side a pointed supporting post 12, and having an outlet through a flexible tube 13. One end of the tube is firmly held in a hole in the cap 11 by a hollow tubular rivet or grommet 14.

The flexible tube 13 has a circular periphery at the end which fits into the cap 11, as indicated by section 2—2 shown in Figure 2. Throughout the remainder of its

2

length, however, the sides of the tube are flattened as indicated at section 3—3, shown in Figure 3, thereby providing for increased flexibility in the direction of the flattened sides. Near the free tip of the tube 13, at section 4—4 shown in Figure 4, the outer dimensions of the tube are reduced, and the circular bore of the tube is expanded, in the direction parallel with the flat outer sides, to a narrow slot which serves as a nozzle.

A typical flexible tube as thus described, which has been found to provide excellent action under customary domestic water pressure of between about 20 and about 60 lbs./sq. in., has an exposed length of two and one-half inches, an original external diameter of three-eighths inch, and a thickness between the flattened sides of five-sixteenths inch near the cap, tapering to seven thirty-second inches near the free tip. The bore of the tube is one-eighth inch in diameter. The body of the flexible tube is formed of the following mixture:

	Parts by weight
20 Polyvinyl chloride ("Geon 121")	200
Plasticizer (dioctyl phthalate)	430
Stabilizer ("Ferro" or equiv. Pb cmpd.)	10
Dye ("Anthraquinone green G base")	0.04

The syrupy mixture is first deaerated in a vacuum, and is then poured into a suitably shaped and cored mold, which is next heated to 350° F. to blend the polymer and plasticizer into a soft rubbery homogeneous product. After cooling and aging, the tube is removed from the mold and installed in the sprinkler.

Natural and synthetic rubbers, and other elastic polymers and blends, have proven effective, but I prefer the formulation hereinabove given as having a desirably high degree of flexibility combined with satisfactory outdoor permanence and as being easily formed into the desired shape.

The sprinkler is assembled by first placing the round end of the flexible tube 13 in the cap 11 through the close-fitting hole provided for the purpose, and then pressing the hollow tubular rivet or grommet 14 into the bore of the tube and against the inner surface of the cap. This grommet forces the walls of the tube tightly against the sides of the containing hole, and holds the tube firmly in place in the cap. Cementing or other means of firmly affixing the tube in the cap are equally effective but somewhat less convenient.

Tubes as above described and illustrated afford a superior means of obtaining the required differential flexing action and are preferred. Other equivalent structures will be apparent, particularly in view of the description as a whole.

The supporting post or rod 12, here illustrated as a continuation of the cap 11, serves to hold the sprinkler in position on the lawn, with the flexible tube pointed upward at a moderate angle and in proper position to emit a wedge-shaped flat sheet of water. The cap 11 provides a means for holding the fixed end of the flexible tube and for connecting to it the source of water, e. g. a conventional garden hose. These elements of my sprinkler may obviously be replaced by other equivalent means for supporting, positioning, and connecting the flexible tube 13. For example, the rod 12 may be replaced by a separate rod or wire, which may be fastened to the cap 11 by a screw clamp or by welding; or the cap may be screwed directly on a fixed metal pipe serving in place of a flexible garden hose. The flexible tube may alternatively be mounted directly in the wall of such a pipe rather than in a separate cap or body member, e. g. by cementing the end of the tube into a hole drilled in the pipe; in this case the pipe serves all three required functions of supporting the fixed end of the tube, connecting the tube to a source of water under pressure, and holding the tube in the required position for sprinkling.

What I claim is as follows:

1. A flexible sprinkler-tube as herein described, having an end portion for fixed attachment to a support, a flexible free portion having an axial plane of maximum flexibility and at right angles thereto an axial plane of minimum flexibility, and a nozzle portion; the cross-section of said flexible free portion being uniformly externally bounded by two opposite equal arcs of a circle and two

opposite, equal and parallel chords of said circle, the outer dimensions of the nozzle portion being no larger and the inner dimensions no smaller than those of the free portion.

2. A flexible tube lawn sprinkler consisting essentially of a short flexible tube, support means for fixedly supporting said tube from one end at a moderate fixed angle with the lawn, and coupling means for connecting said tube at its supported end to a source of water under pressure; said tube having a fixed end portion, a flexible free portion having an axial plane of maximum flexibility and at right angles thereto an axial plane of minimum flexibility, and a nozzle portion; the cross-section of said flexible free portion being uniformly externally bounded by two opposite equal arcs of a circle and two opposite, equal and parallel chords of said circle, the outer dimensions of the nozzle portion being no larger and the inner dimensions no smaller than those of the free portion.

3. A flexible tube lawn sprinkler consisting essentially of a pointed post support member for vertical positioning in the lawn and terminating in a cap member threaded for attachment to a water-hose, and a short flexible tube fixedly connected at one end to said cap and providing an outlet therefrom; said tube having a fixed end portion, a flexible free portion having an axial plane of maximum flexibility and at right angles thereto an axial plane of minimum flexibility, and a nozzle portion; the cross-section of said flexible free portion being uniformly externally bounded by two opposite equal arcs of a circle and two opposite, equal and parallel chords of said circle, the outer

dimensions of the nozzle portion being no larger and the inner dimensions no smaller than those of the free portion.

4. A flexible tube lawn sprinkler consisting essentially of a pointed post support member for vertical positioning in the lawn and terminating in a cap member threaded for attachment to a water-hose, and a short flexible tube fixedly connected at one end to said cap and providing an outlet therefrom; said tube having a fixed end portion, a flexible free portion having an axial plane of maximum flexibility and at right angles thereto an axial plane of minimum flexibility, and a nozzle portion; the cross-section of said flexible free portion being uniformly externally bounded by two opposite equal arcs of a circle and two opposite, equal and parallel chords of said circle, the outer dimensions of the nozzle portion being reduced from those of the free portion, and the axial bore of the tube being expanded within the nozzle portion in a direction parallel to the flat outer sides of the tube.
